(57) **CLAIM**

The ornamental design for a bathroom receptacle, as shown and described.

DESCRIPTION

FIG. 1 is a perspective view showing my new design for a bathroom receptacle;

FIG. 2 is a side elevational view thereof; the elevational view from all sides being identical to FIG. 2;

FIG. 3 is a top plan view thereof; and,

FIG. 4 is a bottom plan view thereof.

The parts delineated in dashed lines form no part of the claimed design.

1 Claim, 4 Drawing Sheets
